UNITED STATES PATENT OFFICE.

CHARLES BUTTERS ROGERS, OF ST. PETER, MINNESOTA.

KITCHEN-CABINET.

SPECIFICATION forming part of Letters Patent No. 399,438, dated March 12, 1889.

Application filed September 11, 1888. Serial No. 285,162. (No model.)

To all whom it may concern:

Be it known that I, CHARLES BUTTERS ROGERS, of St. Peter, in the county of Nicollet and State of Minnesota, have invented a new and useful Improvement in Kitchen-Cabinets, 5 of which the following is a specification.

The objects had in view by this invention are to provide a kitchen-cabinet which shall combine convenience and facility to carry out 10 the purposes of the same; and to these ends the nature of the invention consists of the combination of parts, including their construction, substantially as hereinafter set forth and claimed.

15 In accompanying drawings, Figure 1 is a front elevation of my kitchen-cabinet. Fig. 2 is a side elevation of the same, showing the drawer or box partly withdrawn. Fig. 3 is a 20 sectional elevation thereof with the front down or in a horizontal position. Fig. 4 is a rear elevation of the same, showing additional shelves or leaves thereof in their horizontal or extended position.

25 In the embodiment of my invention I employ an upright case or closure, A, made in its general form. It may be in imitation of a secretary or book-case surmounted with an ornamental heading or entablature. This case or closure is mounted upon casters, so 30 that it may be readily moved about the house or other place. It consists, principally, of a back, a, a contracted top, a', side portions, a², and the upper front portion or door, A'. The lower part of the case or closure A is divided 35 into two compartments by a central partition, b, the front edge of which is preferably curved outward from its lower edge upward to within a short distance of its upper edge, it then being inclined inward and upward, thus forming 40 an angle or offset, as at b'.

B B are drawers or boxes occupying the compartments above referred to, the front portions of which are of the same contour as that of the front edge of the partition b, each 45 thus being formed with an offset or ledge, b², b², ranging in line with the angle or offset b' of said partition, said ledges or offsets virtually forming a single continuous ledge or offset, the purpose of which will appear farther 50 on. The drawers B B rest upon a transverse bridge, b³, secured edgewise to and in between the side pieces, a² a², of the case or closure A,

the bottoms of which drawers stand well above the floor, as do also the bottom edges of the bridge and back of the case, to permit 55 of the ready introduction beneath the same of a broom in sweeping the floor.

The case or closure A is provided in its upper part with shelves for holding various kitchen articles or utensils. The door or upper front portion, A', of the case or closure A is hinged at its lower edge to the upper edge of a cross-piece, a³, fastened to and in between the side pieces, a² a², of the case or closure A just above the drawers B B, permitting 60 said door to swing or open outward and downward. To the outside of said door A' is applied a hinged prop or board, B', which, when the door is lowered into a horizontal position, is adapted to drop into the required 65 position, abutting squarely against the board A' at one edge, the other edge of said prop resting against the inclined part of the partition b and drawers B B, and upon the angle 70 or offset b' and the offsets or ledges b² b² thereof. 75

The board or prop B', as the upper front portion or door, A', is lifted or carried to its upright position and past the perpendicular, thus being caused to stand in or occupy an inward inclined position, will fold upon the 80 door A' and assume the appearance of a panel. At the same time both the door and prop will thus be held in place by gravity, dispensing 85 with a catch or other means to secure the same in place against accidental displacement or falling. The board or prop B' may be beveled upon or provided with a molding around its edges. Applied to the sides of the case A, by hinges are two leaves or additional shelves, C C, arranged thereon at a suitable height, 90 the purpose of which is to hold any culinary article or utensil, or upon them may be set, in cooking at night or during dark, a lamp, or they may be otherwise utilized. The shelves C C have each applied to the rear edge a strip 95 or molding, c, which projects past the sides and a short distance along the back, and is arranged to extend underneath the stop or cleat d, secured to the back of the case or closure A when the leaves or shelves are in 100 their horizontal position. The strips or moldings c of the shelves or leaves C, when the shelves or leaves are in their folded or vertical position, register with additional strips or

moldings $c' c'$ upon the back of casing A, thus uniting with the latter strips or moldings to provide the case or closure A upon its back at the side edges with molding, adding to the finish and adornment thereof.

It will be observed that the offsets or ledges of the drawers B B serve also as hand-holds or drawer-pulls for the convenient and ready handling of the drawers.

10 Having thus fully described my invention, what I claim, and desire to secure by Letters Patent, is—

15 1. The case or closure having at its sides hinged shelves or leaves provided at their rear edges with strips extended beyond the sides, along the back of the case or closure, said case or closure having a stop or cleat upon its back, which engages with the extensions of said strips, substantially as and for the purpose set forth.

20 2. In a kitchen-cabinet, the combination,

with a case provided with a cleat across its back and with a molding along the lower part of its rear edges, of shelves hinged to the sides of the case and provided on their rear edges with rearwardly-projecting strips adapted to engage alternately the cleat and the molding, substantially as herein shown and described.

25 3. The herein-described kitchen-cabinet, consisting of a case provided with the cleat d and the molding c' , the hinged front portion, A', the board B', hinged to the front A' and serving both as a prop and a pawl, and the shelves C, hinged to the sides of the case and provided with rearwardly-projecting strips for engaging alternately the cleat and molding, as specified.

CHARLES BUTTERS ROGERS.
